UNITED STATES PATENT OFFICE.

WILLIAM LAMAR WILLIAMS, JR., OF PITTSBURGH, PENNSYLVANIA, ASSIGNOR TO THE KOPPERS COMPANY, OF PITTSBURGH, PENNSYLVANIA, A CORPORATION OF PENNSYLVANIA.

PUSHER-RAM-CHANGING STATION.

1,351,224.

Specification of Letters Patent. Patented Aug. 31, 1920.

Application filed October 20, 1919. Serial No. 331,959.

To all whom it may concern:

Be it known that I, WILLIAM LAMAR WILLIAMS, Jr., a citizen of the United States, residing in Pittsburgh, in the county of 5 Allegheny and State of Pennsylvania, have invented a new and useful Improvement in Pusher-Ram-Changing Stations, of which the following is a specification.

In coking plants, particularly those of the 10 by-product type, the pusher machine moves lengthwise of the battery from one coking chamber to another in regular timed sequence to push out of the coking chambers or ovens the charges of finished coke. This 15 operation is maintained continuously and consequently it is most essential that proper provision be made for the quick and ready removal of a ram from the pusher machine and the substitution of another ram, should 20 this be necessary for one reason or another. The essential object of this invention is the provision of a ram receiving and supporting station constructed to permit a quick and easy transfer of a ram from the pusher machine and also a similarly efficient transfer 25 of a ram from the supporting station to the pusher machine.

A further object of the invention is to construct the ram receiving and supporting 30 station so that it is especially adapted to receive directly from the pusher machine, without any interference whatsoever, a ram of the usual type having a head depending below the bottom of the ram body or shank 35 and a similarly depending shoe supported in the rear of said head. The station is provided with a plurality of ram-supporting devices movable from an inoperative position, that is clear of the path of movement 40 of the head of a ram, into an operative position behind the head of said ram for supporting the latter behind its head, whereby the ram may be moved head first from the pusher machine on to the frame of the supporting station and a ram supported by the 45 supporting station may be moved in the opposite direction on to the carriage of a pusher machine, without any interference between the ram supporting devices and the 50 head and shoe of the ram.

The invention also includes among its objects an increasing of the efficiency of operation of an apparatus of this character combined with great simplicity in design and 55 construction and such other improvements or advantages in construction and operation

as are found to obtain in the structures hereinafter described or claimed.

In the accompanying drawings, forming a part of this specification, and showing, for 60 purposes of exemplification, a preferred form and manner in which the invention may be embodied and practised, but without limiting the claimed invention specifically to said illustrative instance or instances;

Figure 1 is an end elevation of a pusher ram mounted on the carriage of a pusher machine in position in front of a coke-oven battery;

Fig. 2 is a side elevation of a ram receiving and supporting station showing a pusher ram supported thereon;

Fig. 3 is a top sectional plan view of the ram receiving and supporting station illustrated in Fig. 2;

Fig. 4 is an end view of the same;

Fig. 5 is an enlarged fragmentary transverse sectional elevation taken in a plane indicated by the line 5—5 of Fig. 3;

Fig. 6 is an enlarged fragmentary transverse sectional elevation taken in the plane indicated by the line 6—6 of Fig. 3;

Fig. 8 is a fragmentary side sectional elevation of the parts illustrated in Fig. 7;

Fig. 9 is an enlarged front end view of a pair of ram-supporting devices;

Fig. 10 is a side elevation of one of the trucks illustrated in Fig. 9;

Fig. 11 is a section taken in a plane indicated by the line 11—11 of Fig. 10;

Fig. 12 is a section taken in a plane indicated by the line 12—12 of Fig. 11; and

Fig. 13 is a detailed view of a device for attaching a ram-supporting device to the body of the ram.

Fig. 14 is a diagrammatic plan view illustrating the preferred layout of the coke oven battery, the pusher ram machine and the ram receiving and supporting station.

The same characters of reference indicate the same parts throughout the several views.

The pusher machine illustrated in the accompanying drawings is particularly adapted for use in connection with coke-oven batteries of the by-product type. Such batteries are provided with a plurality of cross-wise extending parallel heating walls and elongated coking chambers intermediate

them, the heating walls being constituted of a series of vertical flame flues and parallel therewith. Coal is introduced into the several coking chambers or ovens of the 5 battery and when the charges of coal in the chambers have been subjected to coking heat for the required period of time, the finished coke in these chambers is pushed out by means of the ram mounted on the pusher 10 machine.

As shown in Fig. 1, the pusher machine embodies in its construction a suitable carriage, indicated by dotted lines at 21, and adapted to travel on a trackway 22, which 15 extends lengthwise along the pusher side of a coke-oven battery, indicated by dotted lines at 23. The carriage 21 supports a reciprocatory ram 24 having the usual head 25 which enters a coking chamber of the oven 20 battery and is made large enough to engage the end face of a charge of finished coke in said chamber; the ram 24 is also provided with an elongated main body portion or shank 26 constructed of structural metal 25 and having along its bottom edge a rack 27. The main body or shank 26 of the pusher ram must necessarily be of great length, inasmuch as it is required that the ram be thrust substantially clear through the length 30 of the coking chamber in order to empty the latter completely of its charge of finished coke. In order to support the ram when traveling through a coking chamber, the head 25 depends beneath the main body 35 or shank 26 of the pusher ram and is provided with a shoe 28 for engaging the bottom of the coking chamber; mounted in the rear of the head 25 is another shoe 29 which also slides on the bottom of the coking chamber. The ram reciprocates on its carriage 40 between a pair of upstanding guide frames 30, 31 which are respectively provided with upper and lower guiding rollers 32, 33 engaging the top and bottom of the main body 45 of the ram. Mounted at the rear of the carriage 21 is a bearing bracket 34 in which is journaled a rear guide roller 35 adapted to engage the rear portion of the bottom edge of the ram. The usual power-driven 50 gearing is provided on the carriage 21 for pushing a ram through a coking chamber and withdrawing the same, said gearing being indicated at 36 and coöperating with the rack 27 to effect forward and back movement of the ram.

In operation, the pusher ram machine is run on the track 22 to a position in front of the coking chamber filled with a charge of finished coke. The ram is then thrust 55 forward through the coking chamber, after the doors of the latter have been removed, and the charge of finished coke is pushed out of the chamber. The ram is then withdrawn and the pusher machine is moved 60 along its track to the next coking chamber 65

filled with a charge of coke ready to be pushed. The charges of coke are pushed from the several chambers of a coke oven battery in regular timed sequence and it is necessary that the pushing operation be 70 effected as soon as the coking of each charge is completed, because of the great temperature within the coking chambers which would effect a rapid combustion of the finished coke. Consequently it is highly 75 important that the pusher ram machine be at all times in condition to perform its work, and in the event that it becomes necessary to remove the ram from the carriage of the pusher ram machine and substitute another ram the operation of interchanging the rams must be effected as quickly and with as great facility as possible. It has frequently been the practice to employ a 80 number of pusher machines, maintaining 85 one pusher machine, at least, in reserve in the event of a breakdown of the other. This, however, involves enormous expense and may be eliminated by the provision of a means for effecting a quick removal and replacement of the ram of the pusher machine.

The present invention provides a ram receiving and supporting station that is adapted to hold in readiness a reserve ram and which is constructed to permit a quick and ready removal of the enormously heavy and bulky ram from the pusher machine to the receiving and supporting station and a subsequent equally quick and easy transfer of the reserve ram from the supporting station 10 to the pusher machine, without the tedious and difficult operation of removing the head or shoe of the ram to permit the shank of the ram to be transferred to rollers or other supports of fixed height on the platform of 10 the ram changing station. In practice the ram receiving and supporting station is positioned beyond a coke oven battery, preferably at one end of the latter, and embodies in its construction a suitable supporting frame consisting generally of two vertical frame sections 37, 38 formed of upright beams 39 braced by diagonal bars 40 and horizontal bars 41. These two vertical frame sections 37, 38 mutually support a 11 horizontal platform 42 formed of structural metal and extending parallel with the direction of movement of a ram on its carriage 21.

Mounted on the platform 42 is a plurality 12 of tracks 43, in the present instance two tracks, each consisting of a pair of the usual rails 44. These tracks 43 are supported by the frame of the ram receiving and supporting station at the end of the coke oven battery in parallelism therewith and lie parallel with and in the path of movement of a ram, the carriage of which is moved to a position in front of the frame of the ram receiving and supporting station. The main operat- 13

- ing level of each track of the pair of tracks 43 inclines downwardly at the receiving end of said tracks, as shown at 45, and merges into a short inoperative track level 46, the 5 latter disposed in a plane beneath the plane of the main portion of the tracks. This lower level 46 of the track 43 is supported by a platform 47 at the receiving end of the ram receiving and supporting station, 10 said platform being provided with stairways 48 whereby an attendant may mount the same to gain access to the tracks. 15
- Movable on each track 43 is a plurality of ram-supporting devices. Each one of these 15 devices consists essentially of a truck or body 49 which forms a bearing for a horizontal axle or shaft 50 on which is mounted, on the opposite sides of the truck 49, rollers 51 running on the rails 44 of a track. Each 20 roller truck thus constructed constitutes a movable support for sustaining a ram on a track 43. The upper portion of the body of each truck is provided with means for effecting an interlocking engagement of the 25 truck with the rack 27 extending along the bottom of a ram, said means being conveniently formed of a toothed segment 52 adapted to interlock with the teeth of a ram rack 27.
- 30 When it is desired to transfer a ram from the carriage of its pusher machine to the ram receiving and supporting station, the several roller trucks 49 of a track 43 are collected together on the inoperative portion 35 46 of the track as shown on the right of Fig. 2. The pusher ram machine having been moved to a position in front of the receiving end of the ram receiving and supporting station, the ram is moved forwardly, 40 by means of the driving mechanism of the pusher ram machine over the track 43. As the several supporting devices or roller trucks 49 have been collected together on the lower inoperative level of the track, the 45 head of the ram and the rear shoe 29, which move in advance of the main body portion or shank 26, pass clear of the tops of the several supporting devices 49 and glide freely over the platform 42 of the receiving 50 and supporting station. As soon as the head and rear shoe of the ram have passed over the supporting device, the first one of them is moved upwardly along the incline 45 of the track on to the supporting level thereof 55 so that the tooth segment of the supporting device engages with adjacent teeth of the rack 27 of the ram and supports the shank of the ram on the track 43. The remaining supporting devices 49 are moved into 60 similar supporting engagement beneath the ram at properly spaced intervals and by the time the ram has been moved clear of the carriage of the pusher machine, it is firmly supported on the track of the ram receiving 65 and supporting station by a plurality of roller trucks 49, spaced at intervals beneath the shank of the ram, as shown in Fig. 2. The ram slides without any obstruction over the platform between the frames 37 and 38 and as it is not necessary to employ cranes or other devices for lifting the ram clear of the carriage of the pusher machine, the transfer of a ram to the receiving and supporting station may be effected with great speed and with great facility and ease. 70
- In transferring a ram from the receiving and supporting station to the carriage of a pusher machine, said carriage is moved to a receiving position in front of the track 43 supporting the ram. The ram is then moved 75 in the opposite direction toward the carriage, and as the shank of the ram travels toward the carriage the supporting trucks 49 are successively rolled along down the incline on to the lower level 46 of the track. 80 By the time the head and rear shoe of the ram have reached the portion 46 of the track, all of the ram supporting devices 49 will have been collected together on that portion, so the head and shoe of the ram 85 may pass freely over them without any obstruction whatever.
- If desired, each supporting device 49 may be attached to the ram before being moved from the lower level 46 of the track upwardly on to the main supporting level thereof, so that the movement of the ram itself will effect movement of each supporting device into supporting position with respect to the ram. For this purpose the body 90 of each supporting truck 49 is provided with a chamber through which is inserted a hook 53 that encircles the axle 50. Secured to the other end of said hook is a rope or other suitable flexible connection 54 which extends to a ring 55 on which is mounted a pair of hooks 56. The hooks 56 may respectively be inserted in holes provided on opposite sides of the shank 26 of the ram, as shown in Figs. 7 and 8. These oppositely-disposed holes will be located at intervals along the shank of the ram and the hooks 56 of each truck 49 may be inserted in said holes as they successively come into position above the lower level 46 of the track. The 95 movement of the ram will thus draw the several supporting trucks 49 up into supporting engagement with the shank of the ram. 100
- The invention as hereinabove set forth is embodied in a particular form of construction but may be variously embodied within the scope of the claims hereinafter made. 105
- I claim:
1. In combination with a pusher ram machine, embodying, a movable carriage, and a reciprocatory ram supported thereby, said ram having a rack extending longitudinally along its bottom and a head and shoe depending below said rack; a ram receiving and supporting station for receiving the 110
  2. In combination with a pusher ram machine, embodying, a movable carriage, and a reciprocatory ram supported thereby, said ram having a rack extending longitudinally along its bottom and a head and shoe depending below said rack; a ram receiving and supporting station for receiving the 115
  3. In combination with a pusher ram machine, embodying, a movable carriage, and a reciprocatory ram supported thereby, said ram having a rack extending longitudinally along its bottom and a head and shoe depending below said rack; a ram receiving and supporting station for receiving the 120
  4. In combination with a pusher ram machine, embodying, a movable carriage, and a reciprocatory ram supported thereby, said ram having a rack extending longitudinally along its bottom and a head and shoe depending below said rack; a ram receiving and supporting station for receiving the 125
  5. In combination with a pusher ram machine, embodying, a movable carriage, and a reciprocatory ram supported thereby, said ram having a rack extending longitudinally along its bottom and a head and shoe depending below said rack; a ram receiving and supporting station for receiving the 130

ram head-first from the pusher machine, comprising, a frame, a continuous track supported thereby parallel with the direction of movement of said ram, said track having a supporting level and a lower level at its receiving end connected by an incline with said supporting level, and a plurality of structurally-independent ram-supporting roller trucks movable on said track and each 10 provided with a toothed member for interlocking engagement with the rack of the pusher-ram, said trucks being respectively movable from the lower level of the track to the upper level thereof behind the head of a ram moving from its pusher machine on to the supporting station to support the ram on the supporting level of the track, substantially as specified.

2. In combination with a pusher-ram machine, embodying, a movable carriage, and a reciprocatory ram supported thereby, said ram having a rack extending longitudinally along its bottom and a head and shoe depending below said rack: a ram receiving and supporting station for receiving the ram head-first from the pusher machine, comprising, a frame, a continuous track supported thereby parallel with the direction of movement of said ram, said track having a supporting level and a lower level at its receiving end connected by an incline with said supporting level, and a plurality of structurally-independent ram-supporting roller trucks movable on said track and each provided with means for engaging the rack of the pusher-ram, said trucks being respectively movable from the lower level of the track to the upper level thereof behind the head of a ram moving from its pusher machine on to the supporting station, to support the ram on the supporting level of the track, substantially as specified.

3. In combination with a pusher-ram machine, embodying, a movable carriage, and a reciprocatory ram supported thereby, said ram having a rack extending longitudinally along its bottom and a head and shoe depending below said rack: a ram receiving and supporting station positioned for receiving the ram head-first from the pusher machine, comprising, a frame, a continuous track supported thereby parallel with the direction of movement of said ram, said track having a supporting level and a lower level at its receiving end connected by an incline with said supporting level, a plurality of structurally-independent ram-supporting roller trucks movable on said track and each provided with a toothed member for interlocking engagement with the rack of the pusher-ram, said trucks being respectively movable from the lower level of the track to the upper level thereof behind the head of a ram moving from its pusher

machine on to the supporting station, to support the ram on the supporting level of the track, and means for attaching said trucks individually to the ram, while the trucks are positioned on the lower level, whereby the movement of the ram effects movement of the trucks on to the supporting level of the track, substantially as specified.

4. In combination with a pusher-ram machine, embodying, a movable carriage, and a reciprocatory ram supported thereby, said ram having a rack extending longitudinally along its bottom and a head and shoe depending below said rack: a ram receiving and supporting station for receiving the ram head-first from the pusher machine, comprising, a frame, a continuous track supported thereby parallel with the direction of movement of said ram, said track having a supporting level and a lower level at its receiving end connected by an incline with said supporting level, a plurality of structurally-independent ram-supporting roller trucks movable on said track and each provided with means for engaging the rack of the pusher-ram, said trucks being respectively movable from the lower level of the track to the upper level thereof behind the head of a ram moving from its pusher machine on to the supporting station, to support the ram on the supporting level of the track, and means for attaching said trucks individually to the ram, while the trucks are positioned on the lower level, whereby the movement of the ram effects movement of the trucks on to the supporting level of the track, substantially as specified.

5. In combination with a pusher-ram machine, embodying, a movable carriage, and a reciprocatory ram supported thereby, said ram having a depending head: a ram receiving and supporting station for receiving the ram head-first from the pusher machine, comprising, a frame, a continuous track supported thereby parallel with the direction of movement of said ram, said track having a supporting level and a lower level at its receiving end connected by an incline with said supporting level, and a plurality of structurally-independent ram-supporting roller trucks movable on said track, from the lower level of the track to the upper level thereof behind the head of a ram moving from its pusher machine on to the supporting station, to support the ram on the supporting level of the track, substantially as specified.

6. In combination with a pusher-ram machine, embodying, a movable carriage, and a reciprocatory ram supported thereby, said ram having a depending head; a ram receiving and supporting station positioned for receiving the ram head-first from the pusher machine, comprising, a frame, a continuous

- track supported thereby parallel with the direction of movement of said ram, said track having a supporting level and a lower level at its receiving end connected by an incline 5 with said supporting level, a plurality of structurally-independent ram-supporting roller trucks movable on said tracks, from the lower level of the track to the upper level thereof behind the head of a ram moving 10 from its pusher machine on to the supporting station, to support the ram on the supporting level of the track, and means for attaching said trucks individually to the ram, while the trucks are positioned on the lower level, 15 whereby the movement of the ram effects movement of the trucks on to the supporting level of the track, substantially as specified.
7. In combination with a pusher-ram machine, embodying, a movable carriage, and a reciprocatory ram supported thereby, said ram having a depending head; a ram receiving and supporting station positioned for receiving the ram head-first from the pusher machine, comprising, a frame, a track supported thereby parallel with the direction of movement of said ram, and a plurality of structurally-independent ram-supporting roller trucks movable from an inoperative position to ram-supporting positions on said 25 track, substantially as specified.
8. In combination with a pusher-ram machine, embodying, a movable carriage, and a reciprocatory ram supported thereby, said ram having a depending head; a ram receiving and supporting station positioned for receiving the ram head-first from the pusher machine, comprising, a frame, a track supported thereby parallel with the direction of movement of said ram and having a supporting 30 level and a lower inoperative level at its receiving end, and means movable from the inoperative level to the supporting level of the track for supporting the ram behind its head, substantially as specified.
9. In combination with a pusher-ram machine, embodying, a movable carriage, and a reciprocatory ram supported thereby, said ram having a depending head; a ram receiving and supporting station positioned for receiving the ram head-first from the pusher machine, comprising, a frame, a track supported thereby parallel with the direction of movement of said ram and having a supporting level and a lower inoperative level at its receiving end, and a plurality of ram supporting devices, each movable from the inoperative level to the supporting level of the track, for supporting the ram behind its head, substantially as specified.
10. In combination with a pusher-ram machine, embodying, a movable carriage, and a reciprocatory ram supported thereby, said ram having a depending head; a ram receiving and supporting station positioned for receiving the ram head-first from the pusher machine, comprising, a frame, and means movable on said frame from an inoperative position, clear of the path of movement of the head of a ram moving on to the frame, into an operative position behind the head of said ram for supporting the latter behind its head, substantially as specified. 65
11. In combination with a pusher-ram machine, embodying, a movable carriage, and a reciprocatory ram supported thereby, said ram having a depending head; a ram receiving and supporting station positioned for receiving the ram head-first from the pusher machine, comprising, a frame, and means movable on said frame from an inoperative position, below the path of movement of the head of a ram moving on to the frame, into an operative position behind the head of said ram for supporting the latter behind its head, substantially as specified. 70
12. In combination with a pusher-ram machine, embodying, a movable carriage, and a reciprocatory ram supported thereby, said ram having a depending head; a ram receiving and supporting station positioned for receiving the ram head-first from the pusher machine, comprising, a frame, and a plurality of ram-supporting devices movable on said frame from an inoperative position, clear of the path of movement of the head of a ram moving on to the frame, into an operative position behind the head of said ram for supporting the latter behind its head, substantially as specified. 75
13. In combination with a pusher-ram machine, embodying, a movable carriage, and a reciprocatory ram supported thereby, said ram having a depending head; a ram receiving and supporting station positioned for receiving the ram head-first from the pusher machine, comprising, a frame, and a plurality of ram-supporting devices, each movable on said frame from an inoperative position, below the path of movement of the head of a ram moving on to the frame, into an operative position behind the head of said ram for supporting the latter behind its head, substantially as specified. 80
14. In combination with a pusher-ram machine, embodying, a movable carriage and a ram supported thereby; a ram receiving and supporting station adapted to receive the ram from the pusher machine, comprising, a frame, and a plurality of ram-supporting devices movable on said frame from an inoperative position clear of the path of movement of a ram moving on to the frame into an operative position beneath the ram for supporting the latter on said frame, substantially as specified. 85
15. In combination with a pusher-ram machine, embodying, a movable carriage, and a reciprocatory ram supported thereby: 90
16. In combination with a pusher-ram machine, embodying, a movable carriage, and a reciprocatory ram supported thereby: 95
17. In combination with a pusher-ram machine, embodying, a movable carriage, and a reciprocatory ram supported thereby: 100
18. In combination with a pusher-ram machine, embodying, a movable carriage, and a reciprocatory ram supported thereby: 105
19. In combination with a pusher-ram machine, embodying, a movable carriage, and a reciprocatory ram supported thereby: 110
20. In combination with a pusher-ram machine, embodying, a movable carriage, and a reciprocatory ram supported thereby: 115
21. In combination with a pusher-ram machine, embodying, a movable carriage, and a reciprocatory ram supported thereby: 120
22. In combination with a pusher-ram machine, embodying, a movable carriage, and a reciprocatory ram supported thereby: 125

- 5 a ram receiving and supporting station adapted to receive the ram from the pusher machine, comprising, a frame, and a plurality of ram-supporting devices each movable on said frame from an inoperative position, below the path of movement of a ram moving on to the frame, into an engaging position beneath the ram for supporting the latter on said frame, substantially as specified.
- 10 16. A ram receiving and supporting station for receiving a ram head-first from a pusher machine comprising in combination: a frame, a continuous track supported thereby parallel with the direction of movement of said ram, said track having a supporting level and a lower level at its receiving end connected by an incline with said supporting level, and a plurality of structurally-independent ram-supporting roller trucks movable on said track and each provided with a toothed member for interlocking engagement with the rack of the pusher-ram, said trucks being respectively movable from the lower level of the track to the upper level thereof behind the head of a ram moving from its pusher machine on to the supporting station, to support the ram on the supporting level of the track, substantially as specified.
- 15 17. A ram receiving and supporting station for receiving a ram head-first from a pusher machine comprising, in combination: a frame, a continuous track supported thereby parallel with the direction of movement of said ram, said track having a supporting level and a lower level at its receiving end connected by an incline with said supporting level, and a plurality of structurally-independent ram-supporting roller trucks movable on said track, and each provided with means for engaging the rack of the pusher-ram, said trucks being respectively movable from the lower level of the track to the upper level thereof behind the head of a ram moving from its pusher machine on to the supporting station, to support the ram on the supporting level of the track, substantially as specified.
- 20 18. A ram receiving and supporting station adapted to receive a headed ram head-first directly from its pusher machine, comprising, a frame, a track supported thereby parallel with the direction of movement of the ram, and a plurality of structurally-independent ram-supporting roller trucks, each movable from an inoperative position, clear of the head of the moving ram, to an operative ram-supporting position, substantially as specified.
- 25 19. A ram receiving and supporting station adapted to receive a headed ram head-first directly from its pusher machine, comprising, a frame, and supporting-means, carried by said frame, movable from an inoperative position, clear of the head of the mov-

ing ram, to an operative ram-supporting position, substantially as specified.

20. A ram receiving and supporting station adapted to receive a headed ram head-first directly from its pusher machine, comprising, a frame, and supporting-means, carried by said frame, movable from an inoperative position, clear of the head of the moving ram, to an operative ram-supporting position behind the head of the ram, substantially as specified.

21. A ram receiving and supporting station adapted to receive a headed ram head-first directly from its pusher machine, comprising, a frame, and supporting-means carried by said frame, movable from an inoperative position, beneath the head of the moving ram, to an operative ram-supporting position behind the head of the ram, substantially as specified.

22. A ram receiving and supporting station adapted to receive a ram from its pusher machine, comprising, a frame, a track supported thereby parallel with the direction of movement of the ram, and a plurality of structurally-independent ram-supporting roller trucks, each movable on said track from an inoperative position, clear of the path of movement of a ram moving on to said station, to an operative ram-engaging and supporting position beneath said ram, substantially as specified.

23. The combination with a coke-oven battery, of a carriage movable lengthwise thereof, and a reciprocatory ram supported by said carriage and movable crosswise with respect to said battery, and a ram receiving and supporting station positioned beyond the coke-oven battery for receiving the ram from the pusher machine, comprising, a frame, and a plurality of ram-supporting devices movable on said frame from an inoperative position, clear of the path of movement of a ram moving on to the frame into an operative position beneath said ram for supporting the latter on said frame, substantially as specified.

24. The combination with a coke-oven battery, of a carriage movable lengthwise thereof, and a reciprocatory ram supported by said carriage and movable crosswise with respect to the battery, and a ram receiving and supporting station positioned beyond the coke-oven battery for receiving the ram from the pusher machine, comprising, a frame, and a plurality of ram-supporting devices each movable on said frame from an inoperative position, below the path of movement of a ram moving on to the frame, into an operative position beneath said ram for supporting the latter on said frame, substantially as specified.

In testimony whereof I have hereunto set my hand.

WILLIAM LAMAR WILLIAMS, JR.
